UNITED STATES PATENT OFFICE.

JOHN P. GRIFFIN, OF PEARCE, ALBERTA, CANADA.

DOOR-CHECK.

1,326,050.

Specification of Letters Patent. Patented Dec. 23, 1919.

Application filed October 26, 1918. Serial No. 259,872.

To all whom it may concern:

Be it known that I, JOHN P. GRIFFIN, a subject of the King of Great Britain, residing at Pearce, Province of Alberta, and 5 Dominion of Canada, have invented certain new and useful Improvements in Door-Checks; and I do hereby declare the following to be a full, clear, and exact description of the invention, such as will enable others 10 skilled in the art to which it appertains to make and use the same.

This invention relates to door checks and has particular reference to a foot operated door check.

15 The principal object of the invention is to provide a simple and inexpensive device of this character which will present a slight appearance and which will be reliable and efficient in use.

20 A further object of the invention is to provide a door check which is of small and compact form and which in operation will not accidentally jar loose and which will yield should the door become violently 25 pushed without liability of injury to the floor.

With these and other objects in view as will appear as the description proceeds, the invention comprises the various novel features of construction, combination and arrangements of parts as will be fully described hereinafter and afterward specifically claimed.

Referring to the drawings, Figure 1 represents a perspective view of the door check attached to the lower part of the door.

Fig. 2 represents a rear elevation of the device with the cover plate removed and showing the parts in inoperative position.

40 Fig. 3 represents a simpler view showing the parts in operative position.

Fig. 4 represents a vertical sectional view taken on a plane indicated by the line 4—4 on Fig. 1, and

45 Fig. 5 represents a sectional elevation of the lower end of the plunger rod and tip.

In order that the construction and operation of the invention may be readily comprehended by those skilled in the art to 50 which the invention relates, I have illustrated an improved embodiment thereof in the accompanying drawings, and will now proceed to fully describe the same, in connection with said drawings in which 1 is the 55 casing of the door check and 2 the cover plate therefor, which latter is provided

with laterally extending ribs 3 to fit within the casing and hold the cover plate against casual displacement with respect to the casing. The device is adapted to be attached to the bottom part of a door by screws or other fastening elements 4 which extend through the casing and cover plate.

60 A spring 5, which may be of leaf spring or spring wire construction, is positioned horizontally within the casing and has one end rigidly but removably connected to the casing as indicated at 6. The casing 1 carries a supporting lug 7 which projects laterally beneath the spring adjacent its anchored end.

65 The free end of the spring is pivotally connected as at 8 to the plunger rod 9 mounted for vertical sliding movement through the bottom of the casing as at 10.

70 This plunger rod has detachably connected to its lower end a floor engaging tip which comprises a metallic socket 11 threadedly connected to the plunger rod and holding a piece of rubber or other desirable floor 75 engaging material 12. This tip is made removable so that it can be readily replaced by another one when it has become worn or unfit for effective use. The rubber or material 12 will prevent the floor from being 80 injured.

85 A lever 13 is positioned horizontally within the casing 1 above the spring 5 and is abnormally in spaced horizontal relation thereto. One end of the lever is provided 90 with a slot 14 to receive a pivot pin 15 carried by the casing, at a point adjacent with where the spring 5 is anchored to the casing. The other end of the lever is provided with a foot piece 16 which projects laterally 95 through the L shaped slot 17 in the casing. The lever 13 is also provided at a point intermediate its ends with a depending finger 18 bearing upon the spring 5 at a point adjacent its free end.

100 In the operation of the device and when it is desired to check the door in open position, the foot piece 16 is depressed and pushed horizontally into the horizontal portion of the L shaped slot 17 where it will 105 remain under tension of the spring 5 until disengaged by the foot. This actuation of the lever 14 will force the plunger rod downwardly until the tip thereof lockingly engages the floor, as clearly shown in Fig. 3.

110 It is to be further noted by this construction that the tip of the plunger rod will be

held in locking engagement with the floor under a yielding spring tension whereby should the door be pushed violently, the plunger will yield from its engagement with 5 the floor without any liability of injuring the floor.

It is to be further understood that the device as described herein can be used with 10 equally as good effect upon a window frame and sash to serve as an anti-rattling device or a window check.

While I have described the principle of operation together with the device I now consider to be the best embodiment thereof, 15 I desire to have it understood that such changes in construction and arrangement of parts may be made when desired as within the scope of the appended claims.

Having thus fully described my invention 20 what I claim as new is:

1. A device of the character described comprising a casing, a plunger slidable therein to bear against a floor or other object, a leaf spring having one end anchored 25 to the casing, said spring engaging said plunger to retract it from the object, and a manually operable member mounted in the casing to contact with the spring and bend it to move said plunger against the object, 30 said member and casing having means for holding said member when moved into contact with the spring.

2. A door check comprising a casing, a spring positioned horizontally within the 35 casing and having one end anchored to the casing, a plunger rod mounted through the bottom of the casing for vertical sliding movement and pivotally connected to the free end of said spring, a lever positioned 40 horizontally within the casing above said spring and provided with means for engagement with said spring, a foot piece carried by the lever projecting laterally through the casing whereby the lever may be depressed to force said plunger into engagement with the floor against the tension of 45 said spring.

3. A door check comprising a casing adapted to be attached to the lower part 50 of the door, a supporting lug carried by the casing adjacent one end thereof, a spring

positioned horizontally within the casing over said supporting lug and having one end anchored to the casing, a plunger rod positioned through the bottom of the casing for 55 vertical movement and having its inner end pivotally connected to the free end of said spring, a lever positioned horizontally within the casing above said spring and provided with means for engagement with 60 said spring, and a foot piece carried by the lever projecting through the casing whereby the lever may be actuated to force the plunger into engagement with the floor against the tension of said spring. 65

4. A door check comprising a casing for attachment to the lower part of a door, a spring positioned horizontally within the casing and having one end anchored to the casing, a plunger rod mounted through the bottom of the casing for vertical movement and pivotally connected to the free end of 70 said spring, a lever mounted within the casing above said spring and having one end provided with a slot, a pivot pin extending 75 through said slot, means carried by the said lever engaging said spring, and a foot piece carried by the free end of the lever and projecting through an L shaped slot in the casing whereby said lever may be depressed 80 and moved longitudinally of the casing to lockingly engage the plunger rod with the floor under spring tension.

5. A device of the character described comprising a casing, a plunger slidable there- 85 in to contact with a floor or other object, a leaf spring anchored within the casing and engaging said plunger to retract it from the object, and a manually - operable lever mounted in the casing and having a portion 90 to bear against the spring and bend it for moving the plunger against the object yielding, said lever and casing having means for holding the lever when it is moved to bend the spring. 95

In testimony whereof I have signed my name to this specification in the presence of two subscribing witnesses.

JOHN P. GRIFFIN.
